UNITED STATES PATENT OFFICE.

SALISBURY M. DAY, OF ROCHESTER, NEW YORK, ASSIGNOR TO GENERAL RAILWAY SIGNAL COMPANY, OF ROCHESTER, NEW YORK, A CORPORATION OF NEW YORK.

RELAY.

Application filed April 9, 1920. Serial No. 372,585.

This invention relates to direct current relays of the tractive type especially designed for use in railway signal systems. The principal object of the invention is to improve and simplify the construction of relays of this type, particularly with the view of providing an organization of parts which can be readily combined or adjusted to fit the various working conditions and requirements found in practice. Other detail objects and advantages will appear hereinafter.

In describing the invention in detail reference will be made to the accompanying drawings in which like reference characters refer to corresponding parts in the several views, and in which:

Figure 1 is a longitudinal section through a relay embodying the invention organized as a neutral relay;

Fig. 2 is a vertical transverse section on the line 2—2 in Fig. 1;

Fig. 3 is a plan view of the parts in the enclosed compartment of the relay, the top plate and coils being removed, this view showing the arrangement of parts for a neutral-polar relay;

Fig. 4 is a fragmentary vertical section taken substantially on the line 4—4 in Fig. 3;

Fig. 5 is an enlarged view of the rear bracket, said view being taken on the line 5—5 in Fig. 1;

Fig. 6 is a fragmentary view showing how the relay may be spring supported on a wall so as to be protected from jar and vibration;

Fig. 7 is a detail section of one of the insulating studs for supporting the contact fingers;

Fig. 8 is a fragmentary view of a contact finger having a carbon or graphite contact element;

Fig. 9 is a fragmentary view of the corner of the relay case, in horizontal section, showing an alternative construction of the glass side walls.

Referring to the accompanying drawings, I have shown my relay organized as a neutral relay (Figs. 1 and 2) and as a neutral-polar relay (Figs. 3 and 4), the change being made from one type to the other by merely adding or changing certain parts. I will describe first the construction of the parts common to both types and then the additional parts and changes required to make up a neutral-polar relay.

My improved relay comprises in general a

top plate or panel 1, a bottom plate or base 2, and glass side walls 3; the whole forming the enclosed chamber or compartment containing the contacts and moving parts of the device. The top plate 1 is made of molded porcelain which is preferably unglazed so that certain surfaces may be finished or ground, and which, after such finishing, is dipped into insulating varnish or similar solution. The base 2 is preferably made of aluminum or similar rustless alloy, or it may be made of iron suitably protected against rust. The glass walls 3 on the four sides of the relay may be molded in one piece, as shown in Fig. 3, or made up of separate plates connected together at their adjacent edges by sheet metal clips 4, as shown in Fig. 9. The top plate 1 and the base 2 are connected by three long screws 5 and 6—6^a, the two front screws 6—6^a being surrounded by a bushing or sleeve 7 of suitable insulating material, in order to avoid accidental grounding of the circuit controlling parts of the relay to the metallic base 2. The top plate 1 is cut away around its edge to provide a recess or rabbet to receive a gasket 8. Similarly, the outer edges of the base 2 are cut away or depressed to receive a similar gasket. These gaskets 8 are preferably made of cork and are shellaced in place. I find cork preferable to felt for this purpose because it does not absorb moisture and conduct it into the relay compartment. It should be noted that there is no ledge or lip around the lower edge of the glass walls 3 to catch water.

In order to permit interchange of air from outside and inside the relay compartment, I provide a ventilating opening in the bottom which is filled with a fine mesh gauze 9 fastened to an eyelet pressed into the hole in the base 2. In case the special conditions do not require such ventilation, the mesh of the screen 9 may be filled with paint or the like.

A bracket 10, substantially inverted U-shape (see Figs. 1 and 5), is fastened to the top plate 1 along its rear edge by a long screw 5 and two other screws 11. The hole in the bracket 10 and top plate 1 for the long screw 5 is made large enough to permit this screw being inserted from the top with the bracket and its attachments in place. The bracket 10 affords a convenient handle or grip for carrying the relay, and also supports a terminal block 12 for the line connections and the coil leads. The terminal block is preferably made

of porcelain, and is fastened to a shelf-like projection integral with the bracket 10 by screws 13 having their heads countersunk in said block. Three binding posts 14 of the usual construction are fastened to this terminal block, the heads of said binding post being countersunk in recesses in the underside of said block. The recesses in the terminal block for the screws 13 and the binding post 14 are preferably filled with sealing wax or similar material. In the sides of the bracket are holes 15 for receiving screws or similar fastening devices so that the relay may be supported on a wall.

15 In the top plate 1 is a large rectangular hole 16 (see Fig. 1) over which is fastened by screws 18 a coil support or plate 17 of brass, aluminum or similar non-magnetic material, the surface of the top plate 1 around this hole 16 being ground to form a tight joint with the coil support 17. On the coil support 17 are mounted the usual pair of coils 19 which have cores 20 pressed into holes in enlarged square pole pieces 21, said pole pieces being fastened to the coil support 17 by screws 22. The cores 20 are connected at their upper ends by the usual back strap 23 of magnetic material. The coils 19 are taped and impregnated, and are held against movement between the back strap 23 and the coil support 17 by inserting the requisite number of thin insulating washers 24 between said coils and the coil support 17.

The armature 25 of the relay consists of a rectangular plate which has a pivot bar 26 riveted thereto near each end. Integral with the coil support 17 are two downwardly extending armature supports or hangers 27 which have holes at their lower ends for receiving trunnion pins 28, said hangers being split and provided with clamp bolts 29 and lock washers to hold the trunnion pins in place. The pivot bars 26 are provided with bearing holes for receiving said trunnion pins 28. In addition to the usual residual pins 30 in the pole pieces 21 (partly shown in Figs. 1 and 4), a stop bar 31, of brass or similar hard non-magnetic material, is fastened across between the two pole pieces 21 by screws 32 (see Fig. 3), the faces of the pole pieces being recessed to receive the ends of said stop bar. In the armature 25 is threaded a screw 33, with the usual lock nut, which strikes the stop bar 31 as the armature is raised to its attracted position, so that by adjusting said screw 33 the minimum air gap may be changed. The armature 25 carries a number of contact fingers, designated as a whole G, which are constructed alike, so that a description of one will suffice for all. Each contact finger G comprises a strip or bar 34 of brass or similar conducting material which is rigidly fastened at one end to the armature 25 by two insulators 35, shown in detail section in Fig. 7. This insulator comprises two

threaded studs 36 each having its head provided with a V-shaped circumferential groove 36^a and also with a cross slot 36^b. The heads of said studs 36 are imbedded in a cylindrical block 37 of molded insulation, with the heads projecting slightly. One stud 36 is screwed into the armature 25 and the other projects through a longitudinal slot in the strip 34 and is clamped thereto by a nut 38. A lock plate 39 is provided for the two nuts 38 associated with each contact finger, the corners of this plate being bent up against the sides of the nuts, as shown in Fig. 1. Between the front insulator 35 and the bar 34 is a clip 40 to which the usual pigtail 41 is fastened. In the particular construction shown, the pigtail 41, which is preferably made of braided copper, is threaded through two spaced slots in the clip 40 and soldered. The other end of the pigtail 41 is fastened to a similar clip 40^a which is connected to a binding post H.

In my improved relay, there are three rows of binding posts supported by the top plate 1 in front of the coils 19. One of these binding posts, designated as a whole H, is the post to which the pigtail 41 is connected, this post being conveniently termed the "heel" post. The binding posts F in the next row support the front contacts, and the binding posts B in the front row support the back contacts. The posts H, F and B are of different heights in step fashion, as shown in Fig. 1. The construction of these different binding posts is the same in many respects, and for convenience corresponding parts will be given the same reference characters with additional exponents.

The post H comprises an elongated head or standard 42, square in cross section, which fits into a square recess formed by a raised ridge 43 on the upper surface of the top plate 1. A round shank 44, integral with the head 42, extends down through the top plate 1 and is threaded at its lower end to receive a nut 45 clamping the binding post in place and nuts 46 for clamping the pigtail clip 40^a. The post has the usual nuts 47 at the upper end for attaching wires; and extending between these nuts and the top plate 1 is a sleeve 48 of suitable insulating material which surrounds the head or standard 42 and protects it against accidental contact with wires attached to the other posts, tools, or metallic articles dropped between the posts. The raised ridges 43 on the top plate 1 prevent small quantities of water, sometimes gathering on the top plates of relays, from getting access to the joint between the binding post and said top plate.

The bar 34 of each contact finger G has riveted thereto near its front end a front contact spring 50 and a back contact spring 51. The front end portion of the bar 34 is reduced in width (see Fig. 2) and is bent down as best

shown in Fig. 1, to engage the back contact spring 51 at its outer end and limit its upward movement. The spring 50 is split into three parts at its outer end (see Fig. 11) and to each part is fastened a tip 52, of coin silver, or other non-corrosive conductive material. The spring 51 has a similar tip 52 fastened thereto.

The front contact member, carried by the binding post F, comprises a stem 55 which is threaded into an axial bore in the binding post F, so that this member may be adjusted up and down. A jam nut and washer 56 on this stem 55 engages the bottom of a recess 15 in the under face of the top plate 1, and not only clamps the binding post F in place, but also locks said stem in its adjusted position. The lower end of the stem 55 is provided with a jaw or socket, in which the contact element 20 57 is fastened by a screw 58. This front contact element 57 is in the form of a rectangular block, with a hole for receiving the screw 58.

In relays for railway signaling, the contacts should be non-fusing, have a low contact resistance, with a relatively small contact pressure, and be capable of maintaining such low resistance in service after a large number of operations. To prevent fusing, one of the 25 contact elements is made of some form of carbon, the other element being any suitable highly conductive non-corrosive metal, such as 99.9% fine silver. The use of a carbon contact element, however, gives a relatively high 30 contact resistance, and to reduce this resistance I impregnate or saturate the carbon element with a small percentage of copper. Instead of carbon in the form of graphite, which has the objectionable greasy property 35 causing it to form in time a film or coating on the metal element, increase the contact resistance, and make it fluctuate in service, I employ a hard dense carbon, having a crystalline structure. A carbon which I find satisfactory for this purpose is an oil or gas furnace product, which is ground up into a fine 40 flour and then pressed together at high temperature with a suitable binder to give a homogeneous and uniform structure. The 45 constituent parts of this carbon are treated and selected so that the carbon is sufficiently porous to receive a small percentage of pure copper. The percentage of copper may be varied, to suit particular conditions. As larger 50 percentages of copper as used, lower contact resistance is obtained, but the tendency to fuse is increased. I find that from about five to fifteen per cent of copper by volume provides a non-fusing element having the desired 55 low contact resistance; and I find ten per cent of copper, or as nearly ten per cent as can be obtained in commercial manufacture, gives satisfactory results under the average conditions found in practice. The impregnation 60 of the carbon with copper is preferably made

by a combined vacuum and pressure process, so that the copper is as uniformly distributed as possible. This contact element is dense and hard, in fact, so hard that it cannot be worked by ordinary tools but must be finished 70 with carborundum wheels or other hard grinding compound. I find that such a carbon contact element gives in practice a low contact resistance with coin silver of approximately .15 to .25 ohms, with a contact pressure of from approximately 1½ to 2 ounces per contact. Moreover, this low contact resistance stays constant in regular service, and will be as low, or perhaps lower, after many 75 operations.

The contact spring 50, carrying the metal contact element, is normally set at an angle with respect to the surface of the carbon element 57 (see Fig. 1), so that when the armature of the relay is attracted, this spring 80 85 is flexed slightly, and the silver tips 52 are slightly wiped or rubbed over the surface of said carbon element. This slide cleans the surface of the contact elements, thereby maintaining them in condition to make an 90 intimate and low resistance contact, and also causes the circuit to be broken at a different point than where the current is carried normally while the relay is energized. The 95 parts are adjusted in manufacture so that the desired contact pressure and rub are obtained.

The back contact comprises a bracket or support 60 which is curved or bent in the shape shown in Fig. 1. This bracket has a flange at its upper end which fits in a slot or recess in the underside of the top plate 1, so as to hold the bracket against turning, and this flange is clamped to the binding post B by a nut 61 provided with a suitable locking clip, as shown in Fig. 2. The back contact member shown in Figs. 1 and 2 comprises a pin 62 of brass or similar material, which is threaded into a horizontal flange integral 100 with the bracket 60, so that it may be adjusted up and down, and is clamped in its adjusted position by a lock nut 63. The enlarged head of this pin 62 has a thin wafer-like contact element 64, of silver or similar material, soldered thereto.

Instead of metal to metal, or metal to carbon contacts, carbon to carbon contacts may be desirable under certain circumstances; and where this is required, I attach a carbon or graphite button 67 to the contact springs 110 115 50 or 51 in the manner best shown in Fig. 8.

The neutral type relay above described may be readily converted into a polar neutral type by adding a polar armature and associated parts shown in Figs. 3 and 4. The 120 polar armature itself comprises two U-shaped permanent magnets 70 fastened together back to back by a bolt 71 and two dowel pins 72 to a cross member 73 of carrier bar C. In this cross member 73 are fixed 125 130

upper and lower pivot pins 75 and 76. The upper pin 75 sets in a bearing hole in a boss or lug integral with the coil support 17, and the lower pin 76 fits in a bearing bushing set into the stop bar 31, so that the carrier bar C and the magnets 70 are supported for movement on a vertical axis in the plane of the pole pieces 21 and above the neutral armature 25. The corresponding ends of the permanent magnet 70 are of opposite polarity and the construction provides for magnetic attraction and repulsion by both pole pieces 21. The carrier bar C extends crosswise of the relay in front of the neutral armature 25 (see Fig. 4) and has two rearwardly projecting side arms 74 to which polar contact fingers 77 are fastened by two insulators 35 constructed the same as the insulators previously described. The weight of the carrier bar C is balanced by a counterweight 78 attached to the rear end of the cross member 73. The polar contact fingers 77 are constructed in a similar way to the neutral fingers and have contact springs with silver tips for engaging polar contacts carried by binding posts P. The binding post P is constructed substantially the same as the front contact post F, except that it is shorter. The polar contact member comprises a stem 79 threaded into an axial bore in the binding post P and provided with a lock nut 80. This stem 79 has a head 81 integral therewith, which is preferably squared to facilitate its turning; and a square carbon or graphite contact element 82 is clamped to the stem 79 below the head 81 by locking nuts 83.

When assembled as a neutral type, my relay affords a contact capacity of six contact fingers (see Fig. 2), each of which may have a front and a back contact; but when assembled as a neutral-polar type, a shorter neutral armature is used to afford space for the polar contacts, and two outside neutral fingers are omitted, as shown in Fig. 3, the same size of case and the same parts in other respects being used in both the neutral and the neutral-polar relays. In the polar-neutral relay the "heel" contact post H of each of the two outside neutral fingers (which are omitted) is used for the binding post P of one of the polar contacts. I prefer to use the same top plate for both the neutral and the neutral-polar relays, and since the location of the binding posts in these two types is different there are some blank spaces which are filled by screw bolts 86, as shown in Figs. 3 and 4.

Relays in practice are often installed in places where they are subjected to considerable jar and vibration, which is sometimes violent enough to cause improper opening of the contacts. To obviate this difficulty, I arranged to float the relay on shock absorbing or cushioning springs so as to take up

the vibration. When the relay is used as a shelf type, three helical springs 87 are attached to the underside of the base 2 by screws 88 threaded into the bosses for the long screws 5 and 6-6^a. These springs 87 are made stiff enough to support the relay freely, but are made sufficiently resilient to take up the shock and vibration. Three springs are used to afford a 3-point support. When the relay is supported from a wall, a pair of flat springs 75 89 is provided, as shown in Fig. 6. These springs are curved in the manner illustrated and are anchored by screws 90 at their upper ends. These springs 89 have headed rivets or bolts 91 which fit in the holes 15 of the bracket 10.

In order that the contact fingers and armature may not shake around and vibrate in shipment, a cord or other insulated flexible element 92 is looped over two of the middle fingers, as shown in Figs. 1 and 2, and the ends are carried down through a hole 93 in the base 2 and clamped by a screw and washer 94. When the cord 92 is drawn tight, the contact fingers are held down against their back contacts. When the relay is installed and ready for service, the screw 94 is loosened, and the cord 92 released, so that the contact fingers may move freely up and down. The cord 92 may be left in place, or removed, as desired. If the cord is left in place, it is only necessary to tighten it again when it is required to transport the relay.

Among the important features of my improved construction of relay, it should be noted that both the front and back contacts are adjustable from inside the compartment, but once this adjustment has been made in manufacture, it cannot be changed without breaking the seal and opening up the relay. Both the front and back contact elements may be easily replaced, the carbon block 57 being readily removable, and likewise the screw 62. The use of a hard carbon, impregnated with copper, for the carbon contacts makes the contact resistance between carbon and metal lower and more uniform during the life of the relay, while at the same time not sacrificing any of the advantages or non-fusing characteristics of a metal to carbon contact. I find, however, that the percentage of copper should not ordinarily exceed ten per cent in order to avoid any likelihood of the contacts fusing under severe conditions. When the armature is attracted, the contact spring 50 is bent and its tips 52 scraped or rubbed over the surface of the front contact element. This keeps the surface of this contact element clean and in connection with the copper impregnated carbon contact provides a low contact resistance which remains substantially uniform in service.

The various binding posts have been arranged to facilitate connection of the various wires thereto, whether the relay is used

as a shelf or as a wall type. The arrangement of the three rows of binding posts in staggered or step fashion gives added accessibility to these binding posts, enables tools to be 5 more easily applied, and facilitates the connections and identification of the various wires.

The various parts are specially arranged and constructed so that the various types and 10 contact groupings for relays required in practice may be obtained with a small number of parts. For example, the same top plate, coils, and a large number of other parts are common to the neutral or neutral polar relays, either wall or shelf type; and by the 15 appropriate selection and arrangement of binding posts and contacts, any desired contact grouping, within the capacity of the device, may be obtained. In short, the device is 20 constructed as far as practicable so as to be universal in its application to the different conditions found in practice.

In explaining the nature of my invention I have shown and described certain specific 25 forms, without attempting to show or describe the various alternative constructions; and I desire to have it understood that this drawing and description is merely illustrative of my invention and does not exhaust 30 the various embodiments which my invention may take.

What I desire to secure by Letters Patent of the United States, is:—

1. A tractive type relay for railway signaling comprising a top plate of insulating material having a large hole therein, a plate of non-magnetic material having holes therein smaller than said large hole and disposed over said large hole, cores supported by and 40 passing through the holes in said plate and having enlarged pole pieces projecting below said plate, an armature supported below said pole pieces, a base, and glass walls confined between the top plate and base to form 45 a casing, whereby the relay mechanism including said plate, cores and armature can be removed as a unit.

2. A relay, comprising, a top plate, coils carried by the top plate, an inverted U-shaped bracket fixed to one edge of the top plate, suspending slots in the bracket, a projecting shelf at the top center of the bracket, a terminal block fixed to the shelf, and binding posts carried by the terminal block sub- 55 stantially on a level with the tops of the coils.

3. A relay for railway signaling, comprising, a top plate supporting coils, an armature, and movable and stationary contacts, an inverted U-shaped bracket attached to the 60 top plate along one edge thereof and affording a grip for supporting the relay against a wall, and a leaf spring fixed to the bracket and wall for supporting the relay and having a yieldable movable part extending between said relay and the wall.

4. A relay for railway signaling, comprising, a top plate having coils supported thereon, cores in said coils projecting through said top plate, an armature, and movable and stationary contacts carried by the plate, an inverted U-shaped bracket fastened to the top plate along one edge thereof, a terminal block attached centrally of the upper end of said bracket, and binding posts for the line and coil leads carried by the block substantially 70 on a level with the top of the coils.

5. A relay of the tractive type, comprising, a pair of cores having enlarged square pole pieces, a stop bar of non-magnetic material bridging across said pole pieces and fastened 80 to both of them, a tilting armature, insulated contact fingers carried by said armature, insulated stationary contacts cooperating with said fingers, and an adjustable stop pin in said armature arranged to strike the non-magnetic stop bar, and thereby limit the 85 movement of said armature and contact fingers.

6. A relay of the tractive type comprising a top plate, a coil support of non-magnetic material attached to said plate, a pair of cores with enlarged square pole pieces fastened to the coil support, a stop bar of non-magnetic material extending from one of said pole pieces to the other and fastened to both of them, spaced armature supports projecting down from said coil support, an armature pivotally supported along one edge on said supports, contact fingers carried by said armature and cooperating with stationary 90 contacts, and a non-magnetic pin with a locking nut threaded into the armature and arranged to engage said stop bar when the armature is attracted and thereby limit the 95 movement of said contact fingers.

7. In a relay of the type described, an armature, a contact finger, and a pair of insulators connecting said finger and armature, each insulator comprising two studs each having a head imbedded in a block of molded 100 insulation, said heads being shaped to present surfaces preventing endwise and turning movement thereof in the insulation, said studs including threaded stems projecting therefrom having shoulders, so that if these 110 stems are threaded into said armature and finger such armature and finger will lock 115 against such shoulder and not against the insulation.

8. In a relay of the type described, the combination with a top plate of insulating material having a large oblong opening therein, a plate of non-magnetic metal disposed over said opening fastened to said top plate having two hangers depending therefrom, 125 cores of magnetic material passing through said metallic plate terminating in enlarged pole pieces, coils on said cores, an armature pivotally supported by said hangers so as to bridge from one to the other of said pole 130

pieces, and contact mechanism operated by said armature, said opening being of a size to permit the mechanism supported by said metallic plate to be removed therewith 5 through said opening.

9. In a relay, the combination with a top plate of insulating material, a pivotally supported contact finger and means for operating the same mounted under said top plate, a 10 bracket rectangular in cross-section generally vertically disposed having laterally projecting flanges at its ends disposed in parallel horizontal planes, a bolt for securing said bracket to the underside of said top plate, 15 said bracket being shaped to have the lower end disposed on one side of the axis of said bolt and so that a plane passing through said lower end and said bolt is parallel to the flat face of said bracket, a back contact member 20 having a stem threaded into the lower end of said bracket adapted to be engaged by said finger, and a jam nut on said stem for locking said contact member in its adjusted position.

25 10. In a relay, the combination with a top plate of insulating material, a bracket secured at its upper end to the underside of said top plate, said bracket having a horizontal projecting flange at its lower end, a back contact member having a stem threaded into said flange with a jam nut for locking it, said contact member having an enlarged head for engaging the cooperating contact spring or finger.

30 11. In a relay of the type described, an armature, a contact bar attached to said armature by insulators, an insulated binding post, 35 perforated clips sleeved on and clamped and electrically connected to said contact bar and binding post respectively, said clips having 40 projecting tongues with spaced aligned slots therein, and a pigtail connection having its ends looped and soldered in the slots in said tongues.

45 12. A polar armature construction for relays comprising a carrier bar having a cross member, lateral extending extensions on the ends of said bar, contact supports fastened to but insulated from said extensions, and 50 two U-shaped permanent magnets fastened back to back to said cross member by a middle bolt and two dowel pins.

55 13. A polar armature construction for relays comprising a carrier bar having a middle cross member and two laterally extending end portions, U-shaped permanent magnets fastened back to back to said cross member, by a bolt and two dowel pins, a set of insulated contact fingers carried by each of the end portions of said carrier bar, said sets extending 60 away each from the other, and means for supporting said carrier bar for oscillation in the plane of said magnets.

65 14. A relay of the type described comprising a non-magnetic coil support, a pair of

cores having enlarged pole pieces secured to said support, a non-magnetic stop bar extending between said pole pieces and fastened thereto, and a polar armature pivotally supported by the coil support and stop bar on a 70 vertical axis.

75 15. In a relay, the combination of a base, a top plate of insulating material having a large opening extending therethrough near one side thereof, a plurality of rows of binding posts secured in said plate near the opposite side thereof, a plate of non-magnetic metal disposed over said opening, electromagnet structure supported by said top plate including coils above said plate enlarged pole 80 pieces below said plate and an armature associated with said pole pieces, and contact mechanism operated by said armature, whereby the electro-magnet structure may be removed as a unit without disturbing said 85 binding posts.

90 16. In a relay having an armature and a plurality of movable contact fingers carried thereby, stationary front and back contacts cooperating with said fingers, said fingers being enclosed in a compartment, and flexibly insulated means connected to said fingers and operable from outside of the compartment for holding the fingers stationary during shipment.

95 17. A top plate for relays of moulded porcelain having a plurality of round holes surrounded by a ridge projecting above the surface of said plate and arranged in the form of a square, said top plate having a large hole therein through which the cores, pole pieces and armature supports of the relay pass, the upper surface of said plate around the large hole being ground to make a tight joint with the coil support, the top plate being unglazed to permit such grinding and being thereafter dipped in insulating varnish.

100 18. A relay for railway signaling comprising, a top plate of insulating material having coils supported thereon, armature and stationary contacts of the relay, a base and glass side walls forming with the top plate an enclosed compartment for the contacts, a bracket of inverted U-shape attached to the top plate along one edge, and a plurality of 105 long screws connecting the top plate and base, one of said screws passing through said bracket.

110 19. A relay for railway signaling purposes comprising, a porcelain top plate having coils supported thereon, armature and stationary contacts of the relay, a metallic bracket of inverted U-shape fastened to said top plate along one edge with the outer face of said bracket substantially flush with the corresponding outer edge of said top plate; and a terminal block secured to said bracket, said bracket having spaced holes therein adapted to receive fastening members and support the relay on a wall.

20. In a relay of the type described, a porcelain top plate having a large rectangular hole therein, a non-magnetic coil support secured to said top plate over said hole, a pair of 5 cores with enlarged pole pieces extending through said top plate, said pole pieces being fastened to said wall support, coils on said cores, a tilting armature pivotally supported on a horizontal axis from said coil support 10 below the pole pieces, a bracket fastened to said top plate along one edge and having an opening therein so as to afford a grip for carrying the relay, and insulated binding posts secured to the upper edge of said bracket substantially 15 on a level with the upper ends of said coils.
21. In a relay of the type described, the porcelain top plate having a large rectangular hole therein, a non-magnetic coil support secured to said top plate over said hole, a pair of 20 cores with enlarged pole pieces extending through said top plate, said pole pieces being fastened to said wall support, coils on said cores, a tilting armature pivotally supported 25 on a horizontal axis from said coil support below the pole pieces, a carrier bar having a middle cross member and two parallel end portions, U-shaped permanent magnets fastened back to back to said cross member, insulated 30 contact fingers carried by said end portions of the carrier bar, a stop bar of magnetic material extending between said pole pieces and fastened thereto and aligned trunnion pins in the middle cross member of 35 said carrier bar and entering bearing holes in said coil support and said stop bar.
22. A relay for relay for railway signaling purposes comprising, a top plate, a pair of cores having enlarged pole pieces supported 40 by said plate, coils on said cores above said plate, a tiltable armature associated with said pole pieces provided with contact fingers having oppositely disposed contact springs, adjustable front and back stationary contacts
- adapted to be engaged by said contact springs, 45 and contacting non-magnetic means on the pole pieces and the armature forming an adjustable stop for limiting the minimum air gap between said armature and pole pieces.
23. In a relay for railway signaling purposes, the combination of a substantial rectangular casing having a top wall provided with a large opening, a relay support mounted in said opening, a pair of pole pieces extending through said relay support, a soft 50 iron armature pivoted to said support and having a plurality of neutral contact fingers extending from one side of said armature to the opposite side of the casing, and a polarized armature pivotally connected to said pole 55 pieces and having a plurality of contact fingers on each of its opposite ends extending at substantially right angles to the neutral contact fingers.
24. A relay for railway signaling purposes 60 comprising, a U-shaped core terminating in large rectangular pole pieces, a non-magnetic bar connecting said pole pieces, a soft iron armature pivotally mounted adjacent said pole pieces and having an adjustable residual 65 pin adapted to engage said bar, and a polarized armature magnetically associated with said pole pieces and pivotally mounted on said non-magnetic bar.
25. In a relay, a substantially rectangular 70 casing, a top plate on the casing, pole pieces in the casing, a neutral armature in the casing below the pole pieces and supported by the top plate adjacent one side of the casing, neutral contact fingers carried by the 75 armature and extending to the opposite side of the casing, a polar armature carried by the top plate adjacent the pole pieces, and fingers carried by the polar armature extending laterally to the two remaining sides of the casing whereby to segregate the neutral fingers from the polar fingers.
